UNITED STATES PATENT OFFICE.

EPHRAIM CHABOT, OF PROVIDENCE, RHODE ISLAND.

AUTOMATIC TRAIN-STOP.

1,223,310.

Specification of Letters Patent. Patented Apr. 17, 1917.

Application filed December 15, 1913. Serial No. 806.

To all whom it may concern:

Be it known that I, EPHRAIM CHABOT, a citizen of the United States, and resident of the city of Providence, in the county of Providence and State of Rhode Island, have invented certain new and useful Improvements in Automatic Train-Stop, of which the following is a specification.

This invention relates to means for automatically stopping trains, if for any reason the engineer fails to observe the signals which are set against him, and has for its object to provide simple, positive and effective means whereby it is impossible for a train to pass a signal that is set to stop or caution position, at a speed greater than that permitted by the road rules, without having the controlling mechanism automatically operated to slow down or stop the train.

20 A further object of the invention is to provide means whereby when the signal is set to danger that it will position certain means which will automatically engage and operate a certain set of mechanism for completely shutting off the steam from the engine, or apply the air brake or both to bring the train to a stop.

A further object of the invention is to provide means whereby when the signal is set to the caution position that it will operate another mechanism which will cause the train to slow down to a predetermined speed without coming to a full stop.

A further object of this invention is to provide means whereby the throttle and braking mechanism cannot be manually released after having been once set until the speed of the train has been reduced to a predetermined rate.

40 With these and other objects in view, the invention consists of certain novel features of construction, as will be more fully described and particularly pointed out in the appended claims.

45 Of the accompanying drawings:

Fig. 1 is a diagrammatic view showing an end elevation of the engine, partly in section, and the signal mechanism in position to automatically operate the engine control mechanism.

Fig. 2 is an enlarged side elevation, partly in section, showing the tripping arms set in the caution or permissive position.

Fig. 2a is a side elevation showing the

tripping arms both set in disengaging or clear position.

Fig. 3 is a perspective view of the air pressure controlling mechanism with the casing partly broken away to better illustrate the operation of said mechanism.

Fig. 4 is a side elevation of the double acting air controlling valve with the casing partly in section, showing both of the contact levers and the controlling cams in normal position.

Fig. 5 is a detail, partly in section, illustrating the arrangement of the pistons and ports whereby a pressure is constantly maintained on the piston valves for normally forcing them apart.

Fig. 5a is a detail in section illustrating the arrangement of ports whereby a movement of either one of the piston valves permits the pressure to pass outward through a pipe to the operating mechanism.

Fig. 6 is an end view of the valve casting on line 6-6 of Fig. 4, illustrating the general arrangement of the inlet and outlet pipes.

Fig. 7 is a side elevation illustrating the action of the controlling spring upon the contact levers to return them to normal after having been actuated.

Fig. 8 is a sectional side elevation of the steam controlling throttle on line 8-8 of Fig. 9.

Fig. 9 is a plan view of the steam controlling throttle.

Fig. 10 is a detail of the latch on the throttle which is released automatically when the throttle lever is moved to the stop or caution position.

Fig. 11 is a plan view, partly in section, illustrating the means for automatically operating the air brake controlling mechanism.

Fig. 12 is a side elevation, partly in section, illustrating the pump for controlling the action of the release valve.

Fig. 13 is a plan view of the release valve mechanism.

Fig. 14 is a sectional elevation of the release valve mechanism, illustrating the movable fulcrum whose position is regulated by the speed of the engine through the release valve control pump.

Fig. 15 is a detail in section showing the release valve in position to release the operating mechanism.

Referring to the drawings, 20 designates the signal post or support on which the usual semaphore signal 21, or other suitable signaling device, is pivotally mounted. To this semaphore I have applied an operating arm 22 which will be moved to positions A, B and C when the semaphore is set to stop, caution, and clear, respectively. On a bracket or other suitable support 23 I have rigidly mounted a trip-arm casing 24, in which is pivotally mounted a gear 25, said gear engaging a pinion 26 on the shaft of which is mounted an engaging or tripping arm 27, and also a pinion 28 on the shaft of which is fixed another engaging or tripping arm 29, the arm 27 being set to move at substantially right angles to that of the arm 29. On the shaft 30 of the gear 25, I have mounted a rearwardly projecting lever 31 which is connected by means of the rod 32 to the lever 22 supported on the semaphore. By this arrangement of mechanism when the semaphore is moved to stop position, as illustrated in Fig. 1, the arms 22 and 31 are moved to raised position which movement causes the gear 25 to rotate and bring the tripping arm 29 into horizontal or engaging position, at the same time throwing the arm 27 into raised or disengaging position. When the semaphore is moved to caution, or permissive position, (permission or caution in this case being understood to mean that the train need not necessarily come to a full stop, but must slow down to a moderate or predetermined speed,) the arms 22 and 31 are moved to position B, which as is illustrated in Fig. 2 moves the arm 27 to a horizontal or engaging position and the arm 29 to a vertical or disengaging position, and when the semaphore is moved to its normal or clear position the arms 22 and 31 are moved to position C, which as indicated in Fig. 2, moves the tripping arms 27 and 29, both out of engaging position permitting the train to pass at any speed without interference.

In Fig. 1, an engine cab 33 is shown as being mounted on the wheels 34, a pair of which are connected through the shaft axle 36. On the upper portion of the cab is supported the air pressure controlling mechanism 37 supported on the standard 38. This controlling mechanism comprises a downwardly extending contact lever 39 fixed to the shaft 40 by the movement of which the absolute stopping mechanism is automatically controlled through the positioning of cam 41 by mechanism hereinafter described. This air pressure controlling mechanism is also provided with an upwardly extending arm 42 fixed to the longitudinal shaft 43 on which is also mounted a cam 44 through the movement of which mechanism the cautionary or permission mechanism herein-after described, is controlled.

When these levers have been moved from their normal positions, by engagement with the semaphore operated tripping arms, and after they have performed their function, they are returned to normal by the action of the spring 45, whose opposite ends are connected to the shoes 46 and 47 held on pins 48 in the dogs 49, whereby when either one of the shafts 40 or 43 is rotated the pressure is brought to bear on one pin only on the rotated dog, which has a tendency to return the shaft to normal as soon as the operating mechanism has performed its function as hereinafter described.

It will also be noted that the cams 41 and 44 controlled by both of these levers 39 and 42, are so shaped that the levers may be moved in the reverse or backward position without permitting the pistons 51 and 52 to operate and the spring 45 will also serve to return these levers to normal if moved in either forward or backward direction. This construction is absolutely necessary to meet the railroad requirements so that a train may back past the signal even though the signal and tripper are set to danger without operating the stopping mechanism.

In order to control the passage of the air pressure through the several pipes to operate on the throttle and braking mechanisms for controlling the speed of the engine, I have provided a cylinder 50 in which I have mounted two pistons 51, 52, and into this cylinder I admit a pressure from the usual air pressure tank 53, see Fig. 1, through pipes 54 and 55, which pressure acts upon both of said pistons to normally force them outward or in opposite directions. The piston 52 is retained in its normal position as illustrated in Figs. 3, 4, 5 and 5', against the pressure by means of the cam 41 while the piston 51 is retained in its normal or closed position by the cam 44, springs 56 and 57 being arranged within the cylinders to return these pistons to normal after having been operated by the pressure as presently described.

When the semaphore is moved to its stop position, or that illustrated in Fig. 1, the tripping arm 29 is positioned to engage the contact lever 39, withdraw the cam 41 from the end of the piston rod 57 and permit the pressure on the piston 52 to move the piston outward. The movement of this piston as will be seen, permits the air pressure which enters through pipe 55 to pass outward through the port 58 and pipe 59 into the throttle operating cylinder 60, see Figs. 1, 8 and 9, which pressure acts upon the piston 61 and drives it inward against the coil spring 62, causes the piston rod 63 to engage the block 64, and through the link 65 raise the latch 66 from the segment teeth 67 to release the throttle lever 68 and at the same time force said throttle lever over to its

extreme position to completely shut off the steam from the engine cylinders. At the same time this pressure of air in passing down through the pipe 59 also passes through the branch pipe 69 into the brake applying cylinder 70 thereby driving inward the piston 71 against its return spring 72 and through the connecting links 73 rotating the brake applying lever 74 carrying the 10 same around to a position to apply the air brakes to their fullest extent and bring the train to a full stop.

In practice it is found that when one train is approaching too close to another, 15 that it is not always necessary for the approaching train to come to a full stop, but should be simply slowed down so as not to approach within the danger zone, in which case, it is necessary that should the engineer omit to observe the signal that the setting 20 of the signal to the cautionary position should automatically operate and control the action of both the throttle and the brakes to set them into position to slow down the train without action on the part 25 of the engineer. To accomplish this I have provided, that when the semaphore is set to the cautionary position, the tripping arm 27 shall be moved into position to engage the 30 contact lever 42, thereby moving it backward and withdrawing the cam 44 from the end of the piston rod 75. This piston 51 is permitted to move outward which movement uncovers the port 76, see Fig. 5^a, permitting the pressure, which is constantly applied through the pipe 55, to pass outward through the pipe 59, and as above explained operate upon the throttle and brake mechanisms to move the same toward the 40 stopping position. In addition to permitting the air to pass outward through pipe 59 the movement of this cautionary piston also uncovers another port, as illustrated in Fig. 4, and permits the pressure to pass outward 45 through the pipe 77, which pressure enters the cylinder 78 in the throttle mechanism and forces down the piston 79 against its return spring 80, and positions its piston rod 81 as an abutment in the path of movement of the throttle lever 68, whereby the movement of said throttle lever is limited, so that only a portion of the steam is shut off when the cautionary mechanism is operated. At the same time the air from the 55 pipe 77 passes through the branch pipe 82, and enters the cylinder 83 on the air brake controlling mechanism, thereby forcing down the piston 84 against the return spring 85 to locate its piston rod 86 as an abutment in the path of movement of the operating piston rod 87, whereby the movement of this air brake setting mechanism is limited in its stroke to apply all the brakes 60 gradually and slow down the train to a predetermined speed.

It is found in practice necessary to provide some measure and means whereby the engineer cannot, upon finding that his mechanism has been set to stop the trains, again operate the levers at will to release the 70 brakes and apply the steam again. At the same time the mechanism must be so arranged that the engineer is permitted to again operate the mechanism to release his throttle and brakes so that he may again apply the steam and release his brakes, after the train has been slowed to a predetermined speed.

In order to accomplish this, I have provided a release valve controlling air pump 88, which pump is actuated from the axle 36 through gears 39 and 90, wrist pin 91 and connecting rod 92, which operates the piston 93 to force the air through the pipe 94 to the release valve controlling mechanism 95. The pressure which enters through the pipe 94 acts upon the piston 96 to force the same upward against the return spring 97 and normally hold the fulcrum block 98 in its up or inoperative position, a portion of the air passing through the vent 99 in the piston and outward through vents 100 in the cylinder. The piston 102, which is arranged so that it may be moved to shut off the air pressure which enters through pipe 54 and passes through pipe 55 to the air pressure control, can only be operated by a movement of the lever 101, and that only when the fulcrum block 98 is in its down position, as illustrated in Fig. 14. Therefore when 100 the train is running at a high speed the pressure is sufficient to act upon the piston 96 and raise the fulcrum block so that a movement of the lever 101 from position *a* to position *b*, would permit the fulcrum pin 103, under action of the links 104 and 105, which latter is connected to the lever 101, to simply move inward and have no effect whatever upon the piston 102 to which the connection 104 is pivoted at 106, but when the speed has been reduced sufficiently so that the pump 88 will not create a pressure on the piston 96, due to the leakage through the aperture 99, sufficient to raise this piston against the action of the return spring 97, then the fulcrum block returns into position so that a movement of the lever 101 from the position *a* to position *b* will force the release piston 102 outward and so cut off the air pressure from the air pressure controlling mechanism permitting the pistons 51 and 52 to return to normal slowly, under action of their respective springs 56 and 57, thereby permitting the pressure to be relieved from the throttle cylinder 60, motion limiting cylinder 78, brake controlling cylinder 70 and movement limiting cylinder 83, the air from which passing backward through their respective supply pipes into the cylinder 70 and outward therefrom 130

through the pipe 55 back through the release valve 102 and out through the vent port 108. After this pressure has been released from all of these cylinders sufficiently so that they may be again manually operated in the usual way the pistons 51 and 52 resume their normal position ready to again be operated if an attempt should be made to pass the signals unheeded.

10. It will be noted in the operation of the trains equipped with my improved device, that if the engine has previously been slowed down the required amount before passing a signal, which is set to caution or to danger position, my improved mechanism is so arranged that even though the tripper operates the brakes and throttle, they may be immediately restored by the hand of the engineer, and if desired, while running at this slow speed, the engineer may position the release lever 101 so that neither the throttle nor the brake applying mechanism will be operated when the tripper engages either of the contact levers 39 and 42. In other words, an engine cannot run past a signal that is set against it without being stopped automatically, but if the engineer has observed the signal and previously slowed down his train to the required rate, then the operation of the engine still lies within his control.

It will also be noted by the construction of my improved device that both the contact levers 39 and 42 are so constructed as to permit the engine to back past the tripper fingers, even when set, without operating the throttle or brake applying mechanism.

I have shown and described the mechanism as being arranged to shut off the power and also at the same time apply the brakes, but my mechanism may be arranged to either shut off the power without applying the brakes, or apply the brakes without shutting off the power, if desired. If, however, only one of these operations is effected the application of the brakes is considered the most effective.

I claim:

1. An automatic train stop comprising a source of fluid pressure, a fluid pressure motor controlling a source of power, a valve controlling the passage of the pressure fluid to the motor, the pressure of said fluid tending normally to move said valve to open position, a trip member having means for normally resisting opening movement of said valve, and means for temporarily preventing reduction of the fluid pressure against said valve when the same has been moved to open position under predetermined conditions.

2. An automatic train stop comprising a source of fluid pressure, a fluid pressure motor controlling a source of power, a valve controlling the passage of the pressure fluid

to said motor, the pressure of said fluid tending normally to move the said valve to open position, a trip member having means for normally resisting opening movement of said valve, a manual valve controlling the flow of pressure fluid to the first mentioned valve, and automatic means for preventing operation of said manual valve under predetermined conditions.

3. An automatic train stop comprising a source of fluid pressure, a fluid pressure motor controlling the source of power, a valve controlling the passage of the pressure fluid to the motor, the pressure of said fluid tending normally to move said valve to open position, a trip member provided with a rock shaft, having means for engaging said valve, a movable dog on said rock shaft, a spring engaging said dog to maintain said rock shaft in normal position, and means for temporarily preventing reduction of the fluid pressure against said valve when the same has been moved to open position under predetermined conditions.

4. An automatic train stop comprising a source of fluid pressure, a fluid pressure motor controlling the source of power, a valve controlling the passage of the pressure fluid to the motor, the pressure of said fluid tending normally to move said valve to open position, a trip member provided with a rock shaft, a cam on said rock shaft positioned to normally prevent opening movement of said valve, and means for temporarily preventing reduction of the fluid pressure against said valve when the same has been moved to open position under predetermined conditions.

5. In an automatic train stop, a source of fluid pressure, a motor controlling a source of power, fluid pressure mechanism for controlling said motor, a conduit leading from said source of pressure to said controlling mechanism, a valve controlling the flow through said conduit, means for effecting manual operation of said valve, and means for rendering said manual means ineffective under predetermined conditions.

6. In an automatic train stop, a source of fluid pressure, a motor controlling a source of power, fluid pressure mechanism for controlling said motor, a conduit leading from said source of pressure to said controlling mechanism, a valve controlling the flow through said conduit, means for effecting manual operation of said valve, and fluid pressure means controlled by the speed of the vehicle for rendering said manual means ineffective when the vehicle is traveling at or above a predetermined speed.

7. In an automatic train stop, a source of fluid pressure, a fluid pressure motor controlling a source of power, a valve casing having an inlet port leading from said fluid pressure source and an outlet port leading to said motor, a valve in said casing normally

- covering said outlet port, the fluid pressure acting to move said valve in a direction to uncover said outlet port, a rock shaft provided with means for preventing movement of said valve, a dog on said rock shaft provided with pins, a slotted shoe engaging the said pins, and a spring connected to said shoe to hold said rock shaft in a predetermined position and means for maintaining said valve in open position after its release from said holding means. 5 70
8. In an automatic train stop, a source of fluid pressure, a fluid pressure motor controlling a source of power, a valve casing having an inlet port leading from said fluid pressure source and an outlet port leading to said motor, a valve in said casing normally covering said outlet port, the fluid pressure acting to move said valve in a direction to uncover said outlet port, a rock shaft, a cam on said rock shaft arranged opposite the stem of said valve, and means for retaining said cam in a predetermined position and independent fluid pressure means for temporarily preventing shutting off of pressure against said valve. 15 75
9. In an automatic train stop, a source of fluid pressure, a fluid pressure motor, a movable member controlling the source of power, a valve casing having an inlet port leading from said fluid pressure source and an outlet port leading to said motor, a valve in said casing normally covering said outlet port, the fluid pressure acting to move said valve in a direction to uncover said outlet port, means for normally preventing opening movement of said valve, and means connected with said motor for imparting movement to said power controlling member and independent fluid pressure means for temporarily preventing shutting off of pressure against said valve. 20 80
10. In an automatic train stop, a source of fluid pressure, a fluid motor, a throttle lever, means connected with said motor for operating said throttle lever, and means for automatically controlling the supply of fluid from said fluid pressure source to said motor and independent fluid pressure means for temporarily preventing the shutting off of the pressure passing to said motor. 25 85
11. In an automatic train stop, a source of fluid pressure, a fluid pressure motor, a lever, means for locking said lever against movement, means operated by said motor for successively unlocking said lever and moving the same, and means for controlling the passage of fluid from said fluid pressure source to said motor and independent fluid pressure means for temporarily preventing the shutting off of the pressure passing to said motor. 30 90
12. In an automatic train stop, a source of fluid pressure, a fluid pressure motor, means for controlling the supply of fluid pressure to said motor, a lever, means operated by said motor for actuating said lever, and fluid pressure means for temporarily preventing the shutting off of pressure passing to said motor. 35 95
13. In an automatic train stop, a source of fluid pressure, a fluid pressure motor, means for controlling the supply of fluid pressure to said motor, a lever, means operated by said motor for actuating said lever, a movable abutment for limiting the movement of said lever, and means controlled by said fluid pressure control for operating said abutment. 40 100
14. In an automatic train stop, a source of fluid pressure, a fluid pressure motor, a lever operated by said motor, a valve casing having an inlet port leading from said fluid pressure source, and an outlet port leading to said motor, a valve in said casing normally covering said outlet port, the fluid pressure acting to move said valve in a direction to uncover said outlet port, means for normally preventing opening movement of said valve, and means controlled by said valve for limiting the movement of said lever. 45 105
15. In an automatic train stop, a source of fluid pressure, a fluid pressure motor, a lever operated by said motor, a valve casing having an inlet port leading from said fluid pressure source, and an outlet port leading to said motor, a valve in said casing normally covering said outlet port, the fluid pressure acting to move said valve in a direction to uncover said outlet port, means for normally preventing opening movement of said valve, a movable abutment for limiting the movement of said lever, and fluid pressure means controlled by said valve for operating said abutment. 50 110
16. In an automatic train stop, a source of fluid pressure, a fluid pressure motor, a lever controlled by said motor, a valve casing having an inlet port leading from said fluid pressure source and two outlet ports, one of the latter leading to said motor, a fluid pressure device connected with the other outlet port for limiting movement of said lever, valves in said casing normally covering said outlet ports, the fluid pressure acting to move said valves in a direction to uncover said ports, and means for normally preventing opening movement of said valves. 55 115
17. In an automatic train stop, a source of fluid pressure, a fluid pressure motor, a lever connected with the said motor, a valve casing having an inlet port leading from said fluid pressure source and two outlet ports one of which leads to said motor, a fluid pressure device connected with the other port for limiting movement of said lever, valves in said casing, the fluid pressure acting to move said valves in a direction to uncover said ports, and means for normally preventing opening movement of said valves. 60 120
18. In an automatic train stop, a source of fluid pressure, a fluid pressure motor, a lever connected with the said motor, a valve casing having an inlet port leading from said fluid pressure source and two outlet ports one of which leads to said motor, a fluid pressure device connected with the other port for limiting movement of said lever, valves in said casing, the fluid pressure acting to move said valves in a direction to uncover said ports, and means for normally preventing opening movement of said valves. 65 125
19. In an automatic train stop, a source of fluid pressure, a fluid pressure motor, a lever connected with the said motor, a valve casing having an inlet port leading from said fluid pressure source and two outlet ports one of which leads to said motor, a fluid pressure device connected with the other port for limiting movement of said lever, valves in said casing, the fluid pressure acting to move said valves in a direction to uncover said ports, and means for normally preventing opening movement of said valves. 70 130

tion to successively uncover said outlet ports, and means for normally preventing opening of said valves.

18. In an automatic train stop, a source of fluid pressure, a fluid pressure motor, a lever controlled by said motor, a valve casing having an inlet port leading from said fluid pressure source, and two outlet ports one of which leads to said motor, a

10 movable abutment for limiting movement of said lever, a fluid pressure motor controlling said abutment and connected with the other outlet port, valves in said casing normally covering said outlet ports,

15 the fluid pressure acting to move said valves in a direction to successively uncover said ports, and means for normally preventing opening movement of said valves.

19. In an automatic train stop, a source of fluid pressure, a fluid pressure motor controlling the source of power, a second fluid pressure motor for controlling the source of power to the air brakes, a valve casing having an inlet port leading from said fluid

25 pressure source, and two outlet ports one of which communicates with said motors, a plurality of fluid pressure devices connected with the other outlet port for limiting movement of said levers, valves in said casing

30 normally covering said outlet ports, the fluid pressure acting to move said valves to successfully uncover said ports, and means for normally preventing opening movement of said valves.

20. In an automatic train stop, a source of fluid pressure, a fluid pressure motor controlling a source of power, a valve casing having an inlet port leading from said fluid pressure source and an outlet port leading

40 to said motor, valves in said casing each controlling said outlet port, the fluid pressure acting to move said valves to uncover said outlet port, a rock shaft adjacent each valve, trip arms connected to said rock shafts, dogs

45 connected to said rock shafts, and a spring connecting said dogs.

21. In an automatic train stop, a source of fluid pressure, a fluid pressure motor controlling a source of power, a valve casing

50 having an inlet port leading from said fluid pressure source and an outlet port leading to said motor, valves in said casing each controlling said outlet port, the fluid pressure acting to move said valves to uncover

55 said outlet port, a rock shaft adjacent each valve, trip arms connected to said rock shafts, dogs connected to said rock shafts, fluid pressure means for controlling the position of said fulcrum block, and means operated by a moving part of the train for operating said fluid pressure means.

22. In an automatic train stop, a source of fluid pressure, a motor controlling a source of power, fluid pressure mechanism for controlling said motor, a conduit leading from said source of pressure to said con-

trolling mechanism, a valve controlling the flow through said conduit, a lever connected to said valve, a stop for said lever, and means for moving said stop to release said lever when the train exceeds a predetermined speed.

23. In an automatic train stop, a source of fluid pressure, a motor controlling a source of power, fluid pressure mechanism for controlling said motor, a conduit leading from

75 said source of pressure to said controlling mechanism, a valve controlling the flow through said conduit, a lever connected to said valve, a fulcrum pin connected to said lever, a fulcrum block for said fulcrum pin, and means for moving said fulcrum block

80 out of register with said fulcrum pin when the train exceeds a predetermined speed.

24. In an automatic train stop, a source of fluid pressure, a motor controlling a source of power, fluid pressure mechanism for controlling said motor, a conduit leading from

85 said source of pressure to said controlling mechanism, a valve controlling the flow through said conduit, a lever connected to said valve, a fulcrum pin connected to said lever, a fulcrum block for said fulcrum pin, and fluid pressure means

90 for controlling the position of said fulcrum block.

25. In an automatic train stop, a source of fluid pressure, a motor controlling a source of power, fluid pressure mechanism for controlling said motor, a conduit leading from

95 said source of pressure to said controlling mechanism, a valve controlling the flow through said conduit, a lever connected to said valve, a fulcrum pin connected to said lever, a fulcrum block for said fulcrum pin, and fluid pressure means

100 for controlling the position of said fulcrum block, and means operated by a moving part of the train for operating said fluid pressure means.

26. In an automatic train stop, the combination with a railroad signal, tripping means connected to and operated thereby, of

105 means carried by the train adapted to be operated by contact with said tripping means to shut off the power, means for locking the train stopping mechanism after having been operated, and means including an air pump controlled in its action by the speed of the engine for positioning means

110 whereby the locked mechanism may be released.

27. In an automatic train stop, the combination with a railroad signal, tripping means connected to and operated thereby, of

115 a valve on the engine adapted to be operated by said tripper to admit air pressure to shut off the power, means actuated by the air pressure to limit the amount of power shut off, and means including an air pump controlled in its action by the engine speed for

120 positioning a fulcrum block whereby the

125

130

135

140

stopping mechanism may be again restored to action.

28. In an automatic train stop, the combination with a railroad signal, tripping means connected to and operated thereby, of a piston on the engine connected to the throttle lever, a valve adapted to be operated by said tripper to admit air pressure to said piston to move said lever to shut off the power, and automatic means for limiting the stroke of the throttle lever for reducing the speed of the engine to a predetermined rate.

29. In an automatic train stop, the combination with a railroad signal, tripping means connected to and operated thereby, of a piston on the engine connected to the throttle lever, a valve adapted to be operated by said tripper to admit air pressure to said piston to move said lever to shut off the power, automatic means for limiting the stroke of throttle lever for reducing the speed of the engine to a predetermined rate, and means for permitting the manual op-

eration of the stopping mechanism when the speed of the train has been reduced to a predetermined rate.

30. In an automatic train stop, the combination with a railroad signal, tripping means connected to and operated thereby, of a piston on the engine connected to the throttle lever, a valve adapted to be operated by said tripper to admit air pressure to said piston to move said lever to shut off the power, and automatic means for limiting the stroke of the throttle lever for reducing the speed of the engine to a predetermined rate, a manually operative air pressure control valve and an air pump controlled in its action by the speed of the engine for controlling the operation of said control valve.

In testimony whereof I affix my signature in presence of two witnesses.

EPHRAIM CHABOT.
